UNITED STATES PATENT OFFICE.

FREDERICK E. SIEBENMANN, OF DENVER, COLORADO.

STEAM-HEATING SYSTEM.

No. 921,473.

Specification of Letters Patent.

Patented May 11, 1909.

Application filed November 23, 1906. Serial No. 344,761.

To all whom it may concern:

Be it known that I, FREDERICK E. SIEBENMANN, a citizen of the United States, residing at Denver, in the county of Denver and State 5 of Colorado, have invented certain new and useful Improvements in Steam-Heating Systems; and I do hereby declare the following to be a full, clear, and exact description of the invention, such as will enable others 10 skilled in the art to which it appertains to make and use the same.

This invention relates to improvements in steam heating systems, and particularly to mechanism for creating and holding a vacuum 15 um in the air pipes thereof.

The invention comprises the production of a boiler furnace, radiators, steam pipes for conveying steam from the boiler to the radiators, air pipes connected to the radiators 20 and means connected to the said air pipes for creating and maintaining a substantial vacuum in said air pipes, and also in said radiators.

The object in view is the production of a 25 vacuum chamber connected with the return pipe of the steam heating system, and also connected with the air pipes of said system, means for permitting the creation of a vacuum in said chamber, and means for exhausting 30 air from the air pipes of said heating system and means for permitting the expulsion of air from said vacuum chamber.

With these and other objects in view the invention comprises certain novel constructions, combinations and arrangements of parts as will be hereinafter more fully described and claimed.

In the accompanying drawings:—Figure 1 is a diagrammatic view showing a heating 40 system with a vacuum chamber connected therewith. Fig. 2 is a side elevation of a steam boiler furnace, a vacuum chamber and connecting means. Fig. 3 is a vertical section through a vacuum chamber forming a 45 part of the present invention. Fig. 4 is a side elevation of a vacuum chamber forming a part of the present invention.

Referring more particularly to the drawings, 1 indicates a steam boiler of any desired type. Connected to the boiler 1 is a steam pipe 2 which is adapted to supply any desired number of radiators 3 with steam.

As shown in Fig. 1 the pipe 2 rises from the boiler and the several radiators 3 are in communication therewith and receive steam

therefrom. That a greater number of radiators may be supplied a pipe 4 branches therewith and leads to other radiators, it being understood that pipes 2 and 4, need not be parallel except arranged substantially in parallel horizontal planes. The pipe 4 may be of any approved form and extend to any approved distance and communicates by means of the pipe 40 with the bottom of the boiler 1. The pipe 40 communicates (through 65 the pipe 10) with the vacuum chamber 5 as well as with the bottom of the boiler and serves as a pipe to return the water of condensation from the several radiators to the boilers and to the vacuum chamber as hereinafter described. Connected to the steam pipe 2 is an equalizing pipe 6 that is connected to a pipe 7 in any approved manner as by a T-coupling and communicates with the bottom of the boiler by the means connecting 70 the pipe 40 therewith. Interposed in the pipe 7 between the pipe 6 and the pipe 40 are a manually operated valve 8 and a check valve 9.

The pipe 7 is connected with a pipe 10 80 which in turn is connected with the lower part of the vacuum chamber 5. The return pipe 40 is also connected to the pipe 10 as clearly seen in Fig. 2 of the drawings. A hand operated valve 11 is positioned on pipe 85 10 so as to prevent the return of the condensed steam in pipe 40 from entering exhaust chamber 5 whenever desirable. Under ordinary circumstances the valve 11 is left open so as to permit the water from the 90 condensed steam in pipe 40 to freely enter the vacuum chamber 5. By thus allowing the water in the pipe 40 to freely enter the chamber 5 the water in the chamber 5 is always kept warm by the returned condensed steam. The cooler water in the chamber 5 together with some of the water in the pipe 40 will pass through the valves 8 and 9 and pipe 7 into the boiler 1. As the water passes through valve 9 it will be compelled to lift the check valve 9 as it passes therethrough. This offers a slight resistance which assists in permitting the heated water of condensation in pipe 4 to first enter the 95 vacuum chamber 5 as it is easier to enter chamber 5 than to enter the boiler 1 against the action of the valve 9.

Connected to the upper end of the vacuum chamber 5 is a pipe 12 which in turn is connected to the steam pipe 4. A valve 13 is 100 110

positioned at any convenient point along pipe 12 for closing the same so as to allow steam to enter the chamber 5 from pipe 4 whenever desired and to shut off said steam 5 whenever desired.

The vacuum chamber 5, as more clearly seen in Figs. 3 and 4, is preferably cast in one piece and has formed integrally therewith an auxiliary chamber or pipe 14. The auxiliary 10 pipe is open at 15 and 16. The opening 16 is used principally in cleaning the chamber 14. The opening 15 is connected with the air pipes 17 that are used in connection with the heating system. The air system is pref- 15 erably connected at this point to the chamber 5 in order that any steam that may have gotten into the air pipes and condensed will pass downwardly through the chamber 14 and enter the bottom of chamber 5. As the water in 20 the chamber 5 is always warm, cold water at the top is undesirable and the provision of the chamber 14 will, as will be clearly seen from Fig. 3 of the drawings, effectually direct the cold water to the bottom of the chamber 5. 25 Connected to the chamber 5 is a gage 18 for showing the height of the water in the chamber. Positioned upon the top of the chamber 5 is a smaller chamber or receptacle 19 which communicates with the vacuum 30 chamber 5 through an opening 20. An opening 21 is provided at the top of the chamber or receptacle 19, and in operation is closed by any suitable means as a plug 22 which ex- 35 tends downward into the receptacle 19 and is adapted to close the opening 20 when forced down to its farthest limit. Connected to the receptacle 19 at the opening 23 is a pipe 24 that is provided with a check 40 valve 25. The valve 25 permits the air or other gas under pressure contained in the receptacle 19 to exhaust at that point, or a pipe 26 may be connected to the valve 25 and extend to any convenient place of discharge. 45

As the steam begins to fill the radiators 3, the same will condense as is well known, and return to the boiler 1. The return of the condensed steam as warm water is utilized in operating the vacuum producing mechanism 50 and for creating intermittently a rarefaction in the chamber 5. As the condensed steam returns through pipe 4 in the form of heated water it passes from thence up into the vacuum chamber 5 and keeps the water in 55 vacuum chamber 5 at the same level as in the boiler 1 and at a temperature only slightly below the temperature of the water in boiler 1. As the water in the vacuum chamber 5 cools it will by reason of being 60 heavier than the water in the pipe 40 pass from thence through pipe 10, valves 11, 9 and 8 and pipe 7 into the bottom of boiler 1. Some of the water from pipe 4 also may pass directly to the boiler 1 but a sufficient quan- 65 tity of the water will usually pass into the

chamber 5 as the warm water is lighter than the cold and the resistance of the passage of the water therein is slightly less than into the boiler 1. In this way the water in the chamber 5 is always kept warm so as to produce a 70 vapor in chamber 5. As the water in the chamber 5 gives off vapor it will fill or partially fill the chamber and force out of check valve 25 air from the upper part of the chamber. As the air is forced out of the 75 check valve 25 and is displaced by vapor in the chamber 5 the pressure will be reduced and the vapor being cooled by coming in contact with the cooler upper surface of the chamber 5 will cause a comparatively 80 heavy condensation and a consequent rarefaction. The steam or vapor that is in the chamber 5 is saturated with moisture so that the slightest reduction of pressure by the escape of air from the valve 25 will permit the vapor to come in contact with the cooler 85 portions of the chamber and cause condensation of the vapor. The vacuum thus caused will permit the air, if any, in pipes 17 and radiators 3 to enter chamber 5. The 90 rush of cold air into the chamber 5 condensing the vapor therein will hinder or stop for a short time the production of vapor from the water contained in chamber 5. By thus stopping the vapor the chamber 5 is almost 95 entirely filled with air. After the valve 27 closes by the filling of the chamber 5 the warm water in the chamber 5 will begin to heat the air that has been forced therein and also will give off vapor which, as will be 100 evident, will create a pressure in the chamber 5. This pressure will in turn be permitted to exhaust through valve 25 into the atmosphere. The air as it enters from pipe 17 will keep the upper part of the chamber 5 105 cool and also the air on the outside of the chamber will assist in this. As will be observed the upper part of the chamber 5 is surrounded by air on the outside and contains air comparatively cool on the inside. 110 This provides a chamber with an upper portion that is comparatively cool and a lower portion that is comparatively warm, the lower portion being kept warm by the warm water contained therein. As the vapor continues to rise from the water to force out the air in the upper part of the chamber from the second influx thereof it will rise until it has forced out part of the air, and will by the 115 exhausting of air through valve 25 allow 120 the vapor to expand and again come in contact with the upper, cooler part of the chamber 5, the action being constantly and rapidly repeated.

The warm water in the return pipe 4 is 125 adapted to keep the water in the chamber 5 warm at all times, while the system is in operation. This will permit of the water in chamber 5 to give off vapor as above described. Under some circumstances steam 130

will enter the air pipes 17, and in such instances will, of course, condense and is adapted to enter the auxiliary chamber 14 and pass downward therethrough into the bottom of chamber 5, while the cold air will pass into the upper part of the chamber. During the operation of the heating system the production of vapor and the influx of air into the vacuum chamber 5 are intermittent. The 10 amount of air and the amount of vapor are comparatively small, as after the system has been once put in operation the pipes 17 and the radiators 3 are kept at a substantial vacuum at all times by the continuous automatic operation of the condensing of the steam in chamber 5 and then rising of the steam or vapor in said chamber for the expulsion of cold air therefrom. By the production of a vacuum chamber 5 that will 15 automatically operate as above described, any air that may be permitted to enter any of the radiators 3 or may be formed therein will be removed immediately. This will keep the radiators free for the entrance of steam from 20 the boiler 1 even though the pressure therein 25 may be very low.

In practical operation it has been found that by providing a device according to the present invention the radiators will not cool 30 off entirely for about four or five hours after the fire has been left to die out. After the system has been started as described, and then the fire in the steam boiler furnace 1 permitted to die out, a vacuum will be left in 35 the radiators 3 so that when the fire is again started steam will be easily forced into the radiators 3. If the radiators 3 are found to contain a considerable amount of air, steam may be permitted to enter the vacuum chamber 5 through the pipe 12 and then allowed to 40 condense for forming a vacuum in chamber 5. This will withdraw air from the radiators 3 as above described. If desired, the radiators may also be supplied with automatic 45 air valves.

If desired, steam from the pipe 4 may be permitted to enter the vacuum chamber 5 by opening the valve 13. After the chamber 5 has been filled with steam from the steam 50 pipe 4, valve 13 is closed and the steam in the vacuum chamber 5 is permitted to condense which will cause vacuum therein. The production of the vacuum in the chamber 5 will cause the valve 25 to be tightly closed but the 55 valve 27 to open and draw into the chamber 5 air from the air pipe 17 and the radiators 3. After the vacuum in the chamber 5 has been destroyed by the influx of air, steam may again be forced into the chamber by opening 60 valve 13. By thus admitting steam under pressure into chamber 5 it will force out the air therein through valve 25. After the chamber 5 has been filled with steam and all the air therein forced out the valve 13 is 65 closed and the steam in the chamber 5 is

again permitted to condense which will in turn create a vacuum in chamber 5. This vacuum will act as above described and draw air from the radiators through the pipes 17. After the vacuum has been destroyed the 70 second time, steam may again be permitted to flow into the chamber 5 by opening the valve 13 until all the air contained in the chamber 5 has been forced therefrom. The valve 13 is then closed and vacuum is again 75 allowed to be produced as above described. This operation is continued until all the air in the radiators 3 and the pipes 17 has been removed so as to permit steam from the steam pipe 2 to enter the radiators 3 at atmospheric 80 pressure or below atmospheric pressure. By thus removing the air from the radiators the steam in entering the same will not be compelled to force the air therefrom and consequently resisted thereby. By thus producing a partial vacuum in the radiators the steam from pipe 2 is permitted to enter the same easily. After the heating system has been started in this manner the same will 85 operate automatically as described in the 90 preferred construction and operation.

It is to be distinctly understood that the use of the valve 13 and steam from the steam pipe 4 is simply an adjunct to the present invention and used only to hasten the action of 95 the automatic vacuum chamber. As will be evident the vacuum chamber will operate automatically and the use of steam injected directly into the same is simply to hasten the action, and may be used if desired, but is 100 not essential to the automatic operation of the invention.

A system of heating as provided with the vacuum chamber of the present invention will be adapted to supply steam at all times 105 to the radiators 3 at a lower pressure than if the steam was designed to be forced directly into the radiator against any air that might be contained therein, and in fact steam may be supplied to the radiators at a pressure below atmospheric pressure on account of the vacuum or substantial vacuum in the radiators and air pipes connected thereto. After the system has once been operated and the fire in the steam boiler 1 is kept going even 110 slightly, it will keep the water in the vacuum chamber 5 warm enough to automatically remove any air that might find its way into the radiators 3 or air pipes 17.

Having thus fully described my invention, 120 what I claim as new and desire to secure by Letters Patent is:—

1. In a steam heating system, a boiler, radiating devices connected therewith, a vacuum chamber, means for conducting condensed steam to the lower portion of the chamber from the return main and maintaining the temperature of said lower portion substantially constant, means independent 125 of said first mentioned means for conducting 130

air from the radiating devices to the chamber, above the water line, and bringing the air into direct contact with the walls of the upper portion of the chamber and with the vapor arising from such condensed steam, thereby producing a partial vacuum by the condensation of the vapor, and means permitting the expulsion of air from above a stratum of the vapor by the pressure of such vapor.

2. In a steam heating system, a boiler, radiating devices connected therewith, a vacuum chamber, means for conducting condensed steam to the lower portion of the chamber from the return main and maintaining the temperature of said lower portion substantially constant, means independent of said first mentioned means for conducting air from the radiating devices to the chamber above the water line and bringing the air into direct contact with the walls of the upper portion of the chamber and with the vapor arising from such condensed steam, thereby producing a partial vacuum by the condensation of the vapor, means permitting the expulsion of air from above a stratum of the vapor by the pressure of such vapor, and means for preventing water from entering the upper portion of the chamber through the air inlet.

3. In a steam heating system, a boiler, radiating devices connected therewith, a vacuum chamber, means for conducting condensed steam to the lower portion of the chamber from the return main and maintaining the temperature of said lower portion substantially constant, means independent of said first mentioned means for conducting air from the radiating devices to the chamber, above the water line, and bringing the air into direct contact with the walls of the upper portion of the chamber and with the vapor arising from such condensed steam, thereby producing a partial vacuum by the condensation of the vapor, means permitting the expulsion of air from above a stratum of the vapor by the pressure of such vapor, means for preventing water from entering the upper portion of the chamber through the air inlet and for conducting the water from the air pipes directly to the lower portion of the chamber.

4. In a steam heating system, a boiler, radiating devices connected therewith, a vacuum chamber, means for conducting condensed steam to the lower portion of the chamber from the return main and maintaining the temperature of said lower portion substantially constant, means independent of said first mentioned means for conducting air from the radiating devices to the chamber, above the water line, and bringing the air into direct contact with the walls of the upper portion of the chamber and with the

vapor arising from such condensed steam, thereby producing a partial vacuum by the condensation of the vapor, means permitting the expulsion of air from above a stratum of the vapor by the pressure of such vapor, means for preventing water from entering the upper portion of the chamber through the air inlet, and a pipe for conducting the said water directly to the lower portion of the chamber.

5. In a steam heating system, a boiler, radiating devices connected therewith, a vacuum chamber, means for conducting condensed steam to the lower portion of the chamber from the return main and maintaining the temperature of said lower portion substantially constant, means independent of said first mentioned means for conducting air from the radiating devices to the chamber, above the water line, and bringing the air into direct contact with the walls of the upper portion of the chamber and with the vapor arising from such condensed steam, thereby producing a partial vacuum by the condensation of the vapor, means permitting the expulsion of air from above a stratum of the vapor by the pressure of such vapor, and a pipe for supplying live steam to the upper portion of the chamber at the beginning of the operation.

6. In a steam heating system, a boiler, radiating devices connected therewith, a vacuum chamber, means for conducting condensed steam to the lower portion of the chamber from the return main and maintaining the temperature of said lower portion substantially constant, means independent of said first mentioned means for conducting air from the radiating devices to the chamber, above the water line, and bringing the air into direct contact with the walls of the upper portion of the chamber and with the vapor arising from such condensed steam, thereby producing a partial vacuum by the condensation of the vapor, means permitting the expulsion of air from above a stratum of the vapor by the pressure of such vapor, a return pipe and a pipe leading therefrom connected with the boiler and the vacuum chamber.

7. The combination of a boiler, radiating devices, means connecting said devices with the boiler, a vacuum chamber connected with said means, an air pipe communicating with the radiators, said vacuum chamber comprising a main chamber and supplementary chamber having openings near the upper and lower ends connecting with corresponding portions of the main chamber and an opening at the top in alignment with the main portion of the supplementary chamber, said opening last mentioned connected with the air pipe leading from the radiators, an upper supplementary chamber above the

main vacuum chamber and connected therewith by a suitable passage-way provided with a valve seat, said upper chamber having an opening in its upper wall in alignment with the opening connected with the main chamber, a screw plug threaded in the upper opening, said plug adapted to engage the valve seat, and an air exhaust pipe connected

with an opening in one of the side walls of the upper chamber.

In testimony whereof I affix my signature in presence of two witnesses.
